UNITED STATES PATENT OFFICE.

WILLIAM R. ALLEN, OF CLEVELAND, OHIO, ASSIGNOR TO THE AMERICAN MULTIGRAPH COMPANY, OF CLEVELAND, OHIO, A CORPORATION OF OHIO.

RIBBON-FEEDING MECHANISM.

1,114,327.

Specification of Letters Patent. Patented Oct. 20, 1914.

Application filed February 24, 1913. Serial No. 750,193.

To all whom it may concern:

Be it known that I, WILLIAM R. ALLEN, a citizen of the United States, residing at Cleveland, in the county of Cuyahoga and State of Ohio, have invented a certain new and useful Improvement in Ribbon-Feeding Mechanism, of which the following is a full, clear, and exact description, reference being had to the accompanying drawings.

10 This invention relates to rotary duplicating machines of the type wherein the printing is effected through an inked fabric which travels forwardly with the printing surface at the time of impression and is thereafter retracted. The invention is accordingly in the nature of an improvement on Patent No. 1,004,408, granted Sept. 26, 1911, to The American Multigraph Company as assignee of Harry C. Gammeter.

20 One of the objects of the present invention is to provide simple and efficient mechanism to give a periodic feed to the ribbon independently of its reciprocation, to cause it to present a fresh face to the type on successive impressions.

Another object is to provide the ribbon operating mechanism in such form that the forward feed of the ribbon is coextensive with the actual matter being printed, and 30 independent of the size of the printing drum, so that there is no waste of ribbon surface when the type form is short, as, for example, when printing addresses on envelopes.

35 A third object is to provide a simple device for taking up the forward portion of the ribbon with a practically constant tension, irrespective of the size of the ribbon spool, onto which such forward portion is 40 to be wound.

A fourth object is to provide convenient means for returning the ribbon to the original spool, whenever desired.

The means by which I accomplish these 45 results, and others contributing to the efficiency of the complete machine, will be described hereinafter in connection with the accompanying drawings, which illustrate a preferred form of my invention.

50 In the drawing, Figure 1 is an end view of a rotary duplicating machine, like the multigraph or Gammeter printer, equipped with my ribbon mechanism; Fig. 2 is a front elevation of the same; Fig. 3 is a 55 rear elevation, partly in section Fig. 4 is

a diagrammatic cross section, illustrating the course of the inking ribbon; Fig. 5 is an enlarged section on the line 5—5 of Fig. 1, illustrating the clutch mechanism for the supply spool; Fig. 6 is a detail, being a cross section on the line 6—6 of Fig. 1; Fig. 7 is a fragmentary vertical section on the line 7—7 of Fig. 2 looking toward the right. Fig. 8 is a plan or development of a portion of the drum, showing an address plate which 60 may be used. 65

As shown in Figs. 1 to 4, 1 indicates the bottom portion and 2 and 3 the end standards of the machine frame. Between these standards are mounted the printing drum, 70 designated 5, and the rotary platen, designated 6. The printing drum is preferably a removable segment, as shown at 7 in Fig. 4, mounted on a skeleton drum or frame, consisting of rings 8 on a central shaft 9, 75 the segment being shown as held to this shaft by a hook 10. The shaft extends through the frame member 2 and there has a crank 12, or other suitable means for rotating it. The platen 6 is mounted on an 80 eccentric shaft 13 controlled by a handle or crank 14 on the outside of the frame member 2, whereby the position of the platen with reference to the printing surface may be adjusted. 85

The printing drum may carry on its surface rails or other means for holding a printing surface. As shown, it is provided with rails 16, between which may be mounted type grooved on their sides, as shown at 90 15, Fig. 7. If desired, a suitable address plate 17 carrying type or formed with printing characters, may be mounted on this drum, so that the drum may print the body and address of an addressed letter, or may 95 print the body alone or the address alone, as is well understood. The address plate 17 shown in Figs. 7 and 8 is a slotted plate carrying individual type. As shown, described and claimed in application No. 100 535,747 of H. C. Gammeter (filed Dec. 31, 1909), it is mounted in a recess on the face of the segment, resting on mutilated rails therein, and held by stationary and slidable clips 18 and 19. 105

On the printing drum is a gear 20 meshing with a pinion, not shown, connected with the platen. In printing, the crank 12 is given a left hand rotation and the material to be printed is suitably fed from the front 110

of the machine,—that is from the left hand in Fig. 1,—between the rotating drum and platen, being delivered at the right or rear of the machine.

5 The description so far given applies also to the printing portion of the multigraph and to the machine known as the Gammeter printer. My invention relates to the ribbon holding and feeding mechanism designed to coöperate with such a machine. The ribbon, designated 30, is mounted on a supply spool 31, which is held between two studs 33 and 34 carried on stub-shafts 35 and 36 suitably supported by the end frame members 3 and 2. The stub shaft 35 is mounted in a housing 37 and is pressed by a spring 38 toward the spool, a suitable knurled head 39 on the shaft enabling it to be pulled endwise to release the spool, as desired.

10 The stub shaft 36 carrying the journal pin 34 at the right hand end of the supply spool is part of a clutch, best shown in Fig. 5. As appears in this figure, 40 indicates a suitable bracket or housing secured to the end frame member 2. Journaled on this housing is a bushing 41 having around its periphery gear teeth 42 meshing with an idler 44, which meshes with the main gear 20. A collar 43 held on the other end of 15 the bushing by a suitable set screw completes the mounting of the bushing rotatably in the housing. In the inner face of this bushing is a conical recess 45, in which seats a conical collar 46 surrounding the shaft 36. The shaft itself has a collar 48 seating in a recess in the collar 46, and the collar 46 is held rotatably on the shaft by means of a plate 49 secured by screws on the 20 end of that collar. The plate 49 has a projecting eccentric stud 50 adapted to enter an eccentric opening in the end of the ribbon spool, so that the collar and spool can not rotate independently.

25 The bushing 41 has an intermediate partition 53, and, on the other side of this partition from the conical clutch is a cylindrical recess, in which is mounted a sleeve 54 rigidly secured to the shaft 36, a set screw being shown for this purpose. Between 30 this sleeve 54 and the partition 53 is a helical compression spring 55 surrounding the shaft. It will be seen the tendency of this spring 55 is to draw the shaft outwardly and seat the cone 46 within the seat 45, thus 35 clutching it thereto and preventing any rotation of the spool independently of the rotation of the bushing 41 and hence independently of the drum 5. When, however, the shaft 36 is pushed inwardly, or toward 40 the left, in Fig. 2, the clutch 45 and 46 is free and the spool may turn independently of the drum.

45 The mechanism which controls the clutch just described is a cam block 60 carried by a sliding bar 61 across the end of the ma-

chine. The bar 61 may be conveniently located some distance below the shaft 36 and have an upwardly extending rigid arm 62 carrying the block 60, and this block (which may be really the upper end of the arm) is 50 suitably guided along the inner face of a bar 63 secured to the housing 40. On the bar 61 is a depending rigid arm 65 adapted to be engaged by a roller 66 carried by the crank 12. Such engagement shoves the bar 61 toward the right in Fig. 1, and thus causes the block 60 to force the shaft 36 inwardly, unclutching the clutch and freeing the spool.

55 The crank 12 is located on the opposite side of the circumference from the segment 7, and if this segment is a semi-cylinder, as shown in Fig. 4, the crank is substantially ninety degrees beyond the lower edge of the segment. Thus, when the roller 66 engages the arm 65 to free the spool, the segment is just coming into coöperation with the platen. Accordingly, when the type on the segment do coact with the platen they find the ribbon already freed from the grip of 80 the mechanism described, and the ribbon is thus drawn forward with the paper by reason of the grip of the type and platen.

60 During the forward feed of the ribbon and paper when gripped by the type and platen the forward end of the ribbon is taken up on a suitable reel at the rear of the machine, as hereinafter described. As soon as the type passes out of coaction with the platen, the forward feed of the ribbon 100 ceases. The ribbon remains in that position until the entire possible printing surface,—that is the whole segment,—has moved past the platen. Just after the segment clear the platen, however, the roller 66 comes into coaction with an arm 68 on the bar 61, and this returns the bar 61 to the left (Fig. 1), releasing the shaft 36, and the spring 55 immediately resets the clutch, so that the spool is clamped to the bushing 41. The 110 rotation of this bushing, by reason of it being geared through the idler 44 to the gear 20, is in the direction to wind in the fabric; so that, during the remainder of the 115 rotation of the crank, the supply spool 31 is rotated to wind the fabric upon it. Unless the equivalent of the full segment of fabric was drawn off of the spool during the printing portion of the rotation, the 120 rewinding action will first take up what has been drawn off and then the bushing will slip on the clutch collar 46, the tension of the ribbon, anchored at the other end to the receiving spool, holding the spool 31 against further action.

125 The mechanism heretofore referred to for taking up the forward end of the ribbon, as it is fed forward by the engagement of the printing surface and platen is shown in Figs. 1, 3 and 4. The receiving spool is 130

designated 70. It is mounted on journal pins 71 and 72 carried by two shafts 73 and 74. The shaft 74 is mounted similarly to the shaft 35 at the front of the machine, 5 heretofore described, specifically, the shaft 74 consists of a longitudinally slideable rod mounted in a bushing 76 which is within a housing 77 secured to the frame member 2. The rod has pinned to it a head 78 by which 10 it may be drawn outwardly, and, within the bushing is a compression spring 79 forcing the rod toward the spool. When the head 78 is pulled away from the frame member the spool is released and may be 15 taken out by swinging it clear of the head on the rod 74 and then pulling it lengthwise.

The shaft 73 is provided with an eccentric pin 80 engaging a corresponding opening 20 in the end of the spool, so that this shaft and spool must rotate together. Rigidly mounted on the outer portion of this shaft 73 is a ratchet wheel 82. Journaled on the shaft, and held by a collar 83, is an arm 84 25 carrying a pawl 85. This arm extends downwardly into a notch 86 in the end portion of the sliding bar 61. Accordingly, when the roller 66 on the crank engages the arm 65, and moves the bar 61 toward the 30 right (Fig. 1), as heretofore described, in the rotation of the drum, the arm 83 is swung thereby and the pawl 85 feeds forwardly the ratchet wheel 82 one notch, thus winding in the ribbon a corresponding 35 amount. The gain thus made is held by the detent pawl 88 pivoted at 89 to the bracket 81 which carries the ratchet shaft, this detent pawl holding the spool while the bar 61 shifts toward the left consequent upon the 40 roller 66 engaging the arm 68. Accordingly, each complete rotation of the printing drum results in turning forward the ratchet wheel one tooth and feeding correspondingly the ribbon wound on the 45 spool 70.

To temporarily take up the ribbon fed forward without regard to the amount of ribbon on the spool 70, I provide a reel which is journaled coaxially with the spool 50 and stands outside of it. This reel consists of several bars 90 (six being shown) parallel with the axis of the spools and mounted at their ends in two heads 91 and 92. The head 91 is loosely journaled on the shaft 55 and the bracket 81. The head 92 is loosely journaled on the bushing 76 between a head on that bushing and the bracket 77. Rigidly secured to the side of the head 92 is a gear 94 which meshes with a pinion 95 60 loose on a rod 96 mounted in the brackets 81 and 75. Surrounding this rod is a helical spring 97, one end of which is connected with the pinion 95 and the other end with a collar 98 rigid on the rod. The rod is 65 normally stationary but may be turned by a

knurled head 99 to give the spring the desired tension. The rod may be clamped in adjusted position by a set screw 100 screwing through a stationary boss on the housing 77 against the rod. The spring 97, under 70 tension, tends to rotate the reel, composed of the heads 91, 92 and the bars 90, in a direction to take up the ribbon as fed by the printing surface and platen.

The ribbon 30 passes from the rear or inner face of the supply spool 31 downwardly across the front of the idle roller 102, journaled between points 103 and 104 carried by a bracket 105 and an arm 106 on the bracket housing 40. From this idle roller 80 102 the ribbon passes rearwardly just above the platen 6 and is thus adapted to be impressed by the type and the platen. From thence the ribbon passes to the reel described, which is under the tension of the 85 spring 97. This tension of the spring 97 is constantly applied to the reel. It is not sufficient, however, to pull the fabric against the frictional holding of the clutch 45, 46, nor is it sufficient to draw the ribbon across 90 the type on the segment, even when the clutch is released. Accordingly, the reel is inactive in winding in the ribbon when the printing drum is stationary, but keeps a 95 tension on the ribbon.

Before the printing type come into coaction with the platen, the mechanism heretofore described has released the spool 31, and as soon as this takes place the ribbon feeds freely with the paper toward the rear 100 of the machine. In this movement the ribbon bows outwardly, somewhat, but the reel quickly takes this up by rotating under the action of its spring 97, and thus winds the ribbon onto the bars of the reel surrounding the receiving spool 70. The reel is large enough so that when it has its maximum supply of ribbon wound on it that does not bind the ribbon sufficiently to interfere with the feeding spool 70 being fed to take 105 in the ribbon, such feeding being positive and drawing the ribbon around the reel bars a distance corresponding to one ratchet tooth.

As soon as the type on the drum has 115 passed out of coaction with the platen, the forward feed of the ribbon ceases, for the tension on the reel is not sufficient to draw the ribbon unless fed by the drum, and the ribbon therefore remains in this position 120 until the roller 66 on the crank comes into engagement with the arm 68 and again clutches the supply spool to the bushing 41. This clutching results in the positive gearing of the supply spool in the reverse direction with the drum, so that that drum rotates this spool to wind back the ribbon. The frictional grip of the clutch is 125 sufficient so that the ribbon is pulled back and the reel returned to initial position, thus 130

rewinding the spring 97. When the ribbon has been entirely wound off the reel, further rotation of the drum is provided for by the slipping of the clutch, as before described.

The mechanism so far described reciprocates the ribbon with each printing impression but gradually winds it onto the receiving spool 70, so that a fresh face is presented to the type for each impression. When the ribbon has been entirely wound onto the spool 70 it is necessary either to interchange the spools 31 and 70 or to rewind the ribbon on the spool 31. The interchange may be easily effected by removing both spools from their bearings; passing one of the spools between the drum and platen (when the open space in the drum is downward), mounting the filled spool between the studs 33 and 34; passing the empty spool rearwardly between the drum and platen, and mounting it between the studs 71 and 72.

In place of interchanging the spools, it is very simple to rewind the ribbon directly onto the spool 31 whenever it has accumulated on the other spool. To accomplish this it is only necessary to throw out the ratchet feed, and the mechanism which releases the clutch, and turn down the platen. Then the spool 31 remains positively geared with the drum and rotations of the drum rotate the spool to wind in the ribbon. The gear ratio between the drum and spools multiplies so rapidly that a few rotations of the drum will return the entire ribbon.

To throw out the ratchet feed and the clutch release, I provide the following mechanism, shown in Figs. 1 and 6. I connect the detent pawl 88 with the feed pawl 85 by a link 120, which is pivoted to the pawl 88 and has a loose slot connection with the pawl 85. This makes it normally idle, but when the pawl 88 is turned upwardly to free it from the ratchet (that is to bring it into the position shown in dotted lines in Fig. 1) the link pulls upwardly on the tail of the pawl 85 and frees it from the ratchet wheel. The link in this position lies against the projecting pin 89 on which the detent pawl is mounted, which holds this pawl against turning farther than shown in dotted lines. Now, to prevent the crank from releasing the clutch, as it normally does every time the roller 66 engages the arm 65, I arrange to withdraw the roller out of the path of the arm 65 but not out of the path of the arm 68. It will be noted that the latter arm is considerably wider than the arm 65.

60 The roller 66 on the crank 12 is carried by a pin 125 which has a head 126 and is held in either of two positions by reason of a spring 127 carried by the crank and engaging in annular depressions in the pin.

65 The normal position of the pin and its roller

is that shown in Fig. 6, in which position the roller engages both arms 65 and 68. When, however, the pin is drawn outwardly so that the spring 127 lies in the inner groove 129, the roller misses the arm 65 but 70 engages the arm 68. Accordingly, the clutch stays in mesh and the spool is positively rotated throughout the rotation of the drum, and thus the ribbon may be quickly and easily returned to the supply spool, doing 75 away with the necessity of actually interchanging the spools themselves.

It is convenient to provide means for holding the drum frame stationary to mount the segment thereon, or for other purposes. 80 To accomplish this I may provide a pinion 131 mounted on an arbor 132 which is journaled in a lever 133 pivoted at 134 to the frame of the machine. This arbor carries a hand wheel 135 which is provided with a 85 suitable brake or a spring detent preventing inadvertent rotation. The hand wheel furnishes means for rotating the drum step by step, as desired, and for holding it against displacement. The turning back of the lever 90 throws the mechanism out of gear altogether.

Having thus described my invention, what I claim is:

1. The combination, with a printing couple whose members print by rolling contact, of an inking fabric adapted to extend between the members of the couple, means for advancing the fabric for each cycle of movement of the couple a distance dependent on the length of the printing face, means for taking up the forward portion of the fabric, a spool carrying the rear portion of the fabric, and means including a clutch and gearing for connecting the same with the 100 couple at a non-printing portion of the stroke of the latter.

2. The combination of a rotary printing couple, a pair of ribbon spools having a ribbon mounted thereon and passing between the members of the couple, the ribbon being adapted to be fed forward by the grip of the type and platen, means for taking up the slack caused by such forward feed, and a clutch and gearing adapted to connect the 110 spool carrying the rear portion of the ribbon with the couple at a non-printing portion of the rotation thereof.

3. The combination of a printing couple which prints by rolling contact, of an inked fabric adapted to extend between the members of the couple, pay-out and receiving spools for said fabric, means for periodically and partially rotating said receiving spool to feed in the fabric, and means for 120 taking up the slack independent of either spool.

4. The combination of a rotary printing couple, a fabric adapted to pass between them, a spool on which the forward end of 130

- the fabric may be wound, means for periodically and partially rotating said spool to feed the fabric by short steps, and means on the forward side of the line of printing 5 contact for taking up the slack of the fabric caused by it being ripped and fed by the members of the couple.
5. The combination, with a printing couple, of a spool, means for periodically 10 rotating it to wind in a fabric which may pass between the members of the couple, and a reel surrounding the spool on the same side of the line of printing contact for taking up the slack of the fabric.
- 15 6. The combination, with a printing couple, of a fabric adapted to pass between them, a spool means for rotating it to wind up the fabric, and a reel surrounding the spool for taking up the slack.
- 20 7. The combination of a printing couple, a fabric through which it prints, a spool for receiving said fabric, means for rotating the spool, and a reel mounted coaxially with the spool and having a ribbon-receiving portion 25 outside of and parallel with the axis of the spool.
8. The combination of a printing couple, a ribbon adapted to pass between them, a spool on which the ribbon may be wound, a 30 reel surrounding the spool and rotatable independently thereof, a spring tending to rotate the reel in one direction, and means for giving the spool partial rotations.
- 35 9. The combination, with a printing couple, of a spool, ratchet mechanism operated by the couple to give partial rotations to the spool, a reel outside of the spool, said reel being mounted coaxially with the spool, and a spring tending to turn the reel.
- 40 10. The combination, with a printing couple, of a fabric adapted to pass between the members of the couple, a spool for winding said fabric, ratchet mechanism for rotating said spool, a reel having a ribbon receiving portion outside of the spool, said reel having heads journaled on axes aligned with the axis of the spool.
- 45 11. The combination of a printing couple, a fabric adapted to pass between the members of the couple, a spool for the fabric, a shaft connected with the spool at one end, a ratchet wheel on said shaft, a support for the spool at the other end, a reel having a pair of heads surrounding said shaft and said support respectively and having intermediate rods extending parallel with the spool, and means operated by the printing couple for driving the ratchet.
- 50 12. The combination of a printing couple, a fabric adapted to extend between the members of the couple, a spool for receiving the fabric, a reel surrounding the spool for taking up the slack of the fabric, said reel having a gear, a connecting gear, a rod, and 55 a spring surrounding the rod and connected

with it and at the other end with said connecting gear, whereby the reel is given a tendency to rotate.

13. The combination, with a printing couple, of a fabric adapted to pass between the members of the couple, a spool for receiving the fabric, a reel for taking up the slack in the fabric, a supply spool for the fabric, and a clutch for the same to alternately connect it with and disconnect it from the printing couple.

14. The combination, with a printing couple comprising a rotary drum and a platen, a gear on the rotary drum, a supply spool, a clutch therefor, gearing connecting the clutch with the gear on the drum, and means operated automatically consequent upon the rotation of the couple for clutching and unclutching the clutch.

15. The combination, with a platen, of a printing drum, a supply spool, a clutch at one end thereof, gearing between the clutch and printing couple, means for throwing the clutch into and out of action, a fabric lying between members of the couple and mounted on the spool and extending from it in such direction that the forward rotation of the drum tends to wind back the fabric on the spool, and means controlled by the operation of the couple to hold the clutch disconnected during the printing operation and connect it during a non-printing portion of the rotation.

16. The combination, with a platen and a printing drum coacting therewith, of an inked fabric adapted to pass between them, a supply spool for said fabric, a receiving spool for the fabric, a clutch and gearing adapted to connect the supply spool with the printing couple, ratchet mechanism to feed the receiving spool, and means for throwing said clutch out of action during the printing portion of the rotation.

17. The combination, with a rotary platen, of a printing drum having printing and non-printing portions, a fabric adapted to pass between the drum and platen, a supply spool for the fabric, a receiving spool for the fabric, means including gearing and a clutch for connecting the supply spool with the drum at a non-printing portion of the rotation thereof and freeing it therefrom during the printing portion of the rotation, and means for giving the receiving spool a portion of a rotation during the printing portion of the drum's rotation.

18. The combination, with a platen, of a rotary printing drum having printing and non-printing portions, an inking fabric, a supply spool and a receiving spool therefor, a clutch adapted to be connected with or disconnected from the supply spool, gearing between said clutch and the printing couple, and ratchet mechanism between the printing couple and the receiving spool.

19. The combination, with a platen, of a rotary printing drum having printing and non-printing portions, an inking fabric, a supply spool and a receiving spool therefor, a clutch adapted to be connected with or disconnected from the supply spool, gearing between said clutch and the printing couple, and a take-up reel located outside of the receiving spool.
- 10 20. The combination of a platen, a coöperating printing drum having printing and non-printing portions, a supply spool, a receiving spool, a fabric extending from one spool to the other and passing intermediately between the drum and platen, gearing and a clutch adapted to connect the supply spool with the printing couple, ratchet mechanism for periodically rotating the receiving spool and connected with the printing couple, a take-up reel surrounding the supply spool, means for giving the reel a tendency to stretch the fabric, and means operated automatically by the operation of the couple for clutching and unclutching 25 the supply spool.
21. The combination of a printing couple, a supply spool and a receiving spool, a fabric mounted on said spools passing intermediately between the members of the couple, a clutch mechanism for alternately connecting and disconnecting the supply spool with the couple, periodic feeding means for the receiving spool, and means for throwing out of action periodic feeding means and the disconnection of the clutch to enable the operation of the couple to rewind the ribbon.
22. The combination of a platen, a coöperating printing drum, a supply spool, a receiving spool, a fabric extending from the supply spool between the members of the couple to the receiving spool, clutch mechanism adapted to connect the supply spool with the printing drum, ratchet mechanism adapted to feed the receiving spool, and means for throwing out of action the ratchet mechanism and maintaining the clutch engaged to allow the rotation of the drum to rewind the fabric onto the supply spool.
23. The combination of a rotary printing couple, a supply spool, a receiving spool, a reel around the receiving spool, a fabric mounted on the supply spool and extending between the members of the couple and then across one or more bars of the reel to the receiving spool, spring mechanism tending to rotate the reel to tension the fabric, clutch mechanism adapted to connect the supply spool with the printing couple, mechanism operated by the operation of the couple to throw the clutch alternately into and out of action, and means for maintaining the clutch in continuous connection with the printing couple when desired to return the ribbon.
- 65 24. The combination of a rotary platen, a rotary printing drum having printing and non-printing portions, a crank for rotating the drum, a supply spool, a receiving spool, a fabric having its ends mounted on said spools and extending intermediately between the drum and platen, clutch mechanism connecting the supply spool with the printing drum, ratchet mechanism for rotating the receiving spool, a shiftable bar for throwing the clutch into and out of action and for operating the ratchet mechanism, and means on the crank adapted to shift said bar first in one direction and then the other.
25. The combination of a platen, a rotary printing drum, a supply spool, a receiving spool, a fabric having its ends wound on said spools and passing intermediately between the printing drum and platen, a ratchet for feeding the receiving spool, clutch mechanism for connecting the supply spool with the printing drum, a shiftable mechanism for alternately throwing the clutch and for operating the ratchet, means for shifting said mechanism alternately in opposite directions consequent upon the rotation of the drum, and means for enabling the drum to rotate continuously without causing such shifting.
26. The combination, with a platen, of a printing drum having a gear, a clutch barrel geared therewith, a longitudinally movable shaft in the clutch barrel, a collar carried by the shaft and adapted to clutch with the clutch barrel, a spool connected with said shaft, a fabric mounted on the spool and extending between the drum and platen, and means operated by the rotation of the couple to move the shaft in or out to clutch or unclutch the spool.
27. The combination, with a platen, of a printing drum having a gear, a clutch barrel geared therewith, a longitudinally movable shaft in the clutch barrel, a collar carried by the shaft and adapted to clutch with the clutch barrel, a spool connected with said shaft, a fabric mounted on the spool and extending between the drum and platen, a receiving spool adapted to carry the fabric on the other side of the couple, and shiftable mechanism operated by the rotation of the couple for moving the clutch shaft in or out and for feeding the receiving spool.
28. The combination of a rotary printing drum, a rotator therefor, a rotary impression platen, an inking ribbon extending between the two, spools mounted off of the drum and carrying the wound up ends of the ribbon, mechanism for moving the ribbon in one direction during printing impressions, mechanism driven by the drum rotator for positively moving the ribbon in the opposite direction at a non-printing portion of the rotation, and mechanism for automatically progressing the ribbon by periodically and partially rotating one of the spools.

29. The combination of a rotary printing drum, a rotary impression platen, a ribbon extending between the two spools mounted off of the drum carrying the wound-up ends 5 of the ribbon, a clutch for controlling one of the spools, a ratchet feed for the other spool, a shiftable member controlling the clutch and the ratchet feed, and means oper-

ated by the rotation of the drum for shifting said member.

In testimony whereof, I hereunto affix my signature in the presence of two witnesses.

WILLIAM R. ALLEN.

Witnesses:

ALBERT H. BATES.
